(57) **CLAIM**

The ornamental design for the combined helm and seating for marine vehicle, as shown and described.

DESCRIPTION

FIG. 1 is an isometric view of the combined helm and seating for marine vehicle, illustrated in the environment of marine vehicle;

FIG. 2 is a front isometric view of the combined helm and seating for marine vehicle, illustrated apart from the environment of marine vehicle;

FIG. 3 is a rear isometric view of the combined helm and seating for marine vehicle of FIG. 2;

FIG. 4 is a front view of the combined helm and seating for marine vehicle of FIG. 2;

FIG. 5 is a rear view of the combined helm and seating for marine vehicle of FIG. 2;

FIG. 6 is a right side view of the combined helm and seating for marine vehicle of FIG. 2;

FIG. 7 is a left side view of the combined helm and seating for marine vehicle of FIG. 2;

FIG. 8 is a top view of the combined helm and seating for marine vehicle of FIG. 2;

FIG. 9 is another front isometric view of the combined helm and seating for marine vehicle; and,

FIG. 10 is another rear isometric view of the combined helm and seating for marine vehicle.

The broken lines of FIGS. 1-10 are provided for the purpose of illustrating portions of the article that form no part of the claimed design of the present application. Brackets are shown to illustrate association of elements, but the brackets form no part of the claimed design of the present application.
